RIFLE BROACHING MACHINE

Benedict Welte, Lake Orion, and Harry H. Gotberg, Detroit, Mich., assignors to Colonial Broach Company, Detroit, Mich., a corporation of Delaware

Application January 24, 1942, Serial No. 428,044

4 Claims. (Cl. 90—33)

The present invention relates to a machine for broaching the interior of relatively long tubular members, and is particularly adapted for use in rifling gun barrels.

It has been suggested that in broaching gun barrels and the like the cutting portion of the broach be immersed in oil under pressure, which oil or other suitable coolant is forced through the gun barrel in the direction of the movement of the broach during the broaching operation. The machines hitherto devised for accomplishing this object have not been well suited to mass production methods in view of the fact that they have required a close, non-leaking fit between one end of the gun barrel and a fixture through which the broach passes and to which the coolant under pressure is supplied.

Accordingly, it is one of the principal objects of the present invention to provide a machine for broaching the interior of relatively long tubes, such as is required in the rifle broaching of gun barrels, in which it is unnecessary for the operator to make a leak-proof connection between the gun barrel and the fixture which supplies the coolant under pressure.

A further object of the invention is to provide a machine of the type described in which the broaching operations may be carried on with a minimum of effort on the part of the operator.

Other objects and advantages of the invention will become apparent from the following specification, the drawings relating thereto, and from the claims hereinafter set forth.

Referring to the drawings, in which like numerals are used to designate like parts in the several views throughout:

Figure 1 is a fragmentary, side elevational view of the complete machine, with parts broken away to show the interior construction;

Figure 2 is a fragmentary plan view of the machine;

Figure 3 is a fragmentary, transverse section taken on the line 3—3 of Figure 1;

Figure 4 is an enlarged, longitudinal section of that portion of the machine indicated by the letter A in Figure 1;

Figure 5 is a fragmentary, longitudinal section of that portion of the machine indicated by the letter B in Figure 1;

Figure 6 is a fragmentary, longitudinal section of that portion of the machine indicated by the letter C in Figure 1;

Figure 7 is a transverse section taken on the line 7—7 of Figure 5;

Figure 8 is a transverse section taken on the line 8—8 of Figure 6; and

Figure 9 is a view showing a form of gun barrel adapted to be rifled in the machine.

Referring particularly to Figures 1 and 2, it will be seen that the machine comprises a main base casting 10 of general box-like form provided with a pair of longitudinally extending rails 11 upon which is mounted a longitudinally movable cylinder slide 12.

As best shown in Figure 7, the cylinder in slide 12 is provided with a piston 13, which is connected by means of a double walled piston rod 14 to a manifold 15 by means of which fluid under pressure can be supplied to either side of the piston to effect movement of the cylinder slide. The construction and arrangement of the means for supplying fluid to the cylinder may be of any desired or conventional form, and need not be further described.

A pair of longitudinally extending guide bars 17 are mounted upon the rails 11, and overlie a laterally projecting longitudinally extending rib 18 formed on the cylinder slide 12 to hold the slide in position on the rails 11.

A pull head 20 is secured to the upper surface of the cylinder slide 12 in any suitable manner, and carries a rotatable spindle 21 to which the shank 22 of a broach pulling chuck 23 is secured.

A spiral lead bar 24 is keyed to the spindle 12 by means of a key 25, and projects rearwardly from the pull head 20 through an upstanding boss 26 fixed to the base of the machine at one end of the latter. The boss 26 contains a lead nut 27 provided with internal spiral ribs 28 which fit within the spiral grooves 29 of the lead bar 24 to cause rotation of the latter as the lead bar is moved longitudinally with the pull head 20 and the cylinder slide 12. On the rear face of the boss 26 is mounted a tubular housing 30, which is of sufficient length to entirely enclose the lead bar when it is in its extreme limit of projection at the rear of the machine.

The machine is provided with a work holding fixture indicated generally at 34, which fixture comprises a pair of longitudinally extending base portions 35 connected by a transverse portion 36 having an upstanding transverse wall 37. The longitudinal base portions are adjustably secured to the upper surfaces of guide bars 17 by any suitable means, such as bolts 38. The transverse portion 36 of the work fixture casting is provided with a central longitudinally extending boss 39, provided with a central bore 40 adapted to receive a removable sleeve 41 which is approxi-

mately of the same internal diameter as the external diameter of the large end of the gun barrel or other workpiece.

The sleeve 41 is preferably so dimensioned that it will receive the workpiece with a slip-fit, so that it will hold the workpiece in proper alignment and yet will permit insertion of the workpiece by hand. The sleeve 41 is held in position in the bore 40 by a ring 42 secured by cap screws 43 to the end of the boss 39 and overlying a flange 44 on the end of the sleeve. The sleeve 41 is shorter than the bore 40, and in the right-hand end of the bore is fitted a thrust sustaining ring 45 which is held in position by a cover plate 46 secured to the boss by cap screws 47. The ring 45 is of smaller internal diameter than the sleeve 41, so that the workpiece will abut against the ring when it is positioned within the sleeve. The ring 45 sustains the thrust on the workpiece induced by the broaching operation.

Cover plate 46 is provided with a central opening 48 in which is mounted a ring 49 having a soft metal liner 50 to protect the teeth of the broach from injury. The opening in the liner 50 is slightly larger than the maximum diameter of the broach.

As best shown in Figure 7, the work holding fixture 35 is provided with a means to clamp the work in broaching position. The clamping means is mounted within a transverse bore 52 extending through the boss 39 at right angles to the bore 40 but displaced from the axis of the bore 40. Mounted within the bore 52 is a cylindrical clamping element 53 having an upwardly extending stem 54 upon which is threaded a handle 55. A sleeve 56 surrounds the stem 54 between the handle 55 and the clamping element 53. The cylindrical element 53 and the cylindrical sleeve 56, which are of the same diameter, are of sufficient size to intersect the bore of sleeve 41, but they are cut away, as indicated at 57, in order to conform to the cylindrical contour of the bore in sleeve 41.

Means are provided for preventing rotation of the element 53 and the sleeve 56, which means comprises a pair of set screws 58 and 59 having terminal portions extending into longitudinally extending grooves 60 and 61 in the element 53 and sleeve 56, respectively. It will be apparent that as a result of this arrangement turning of the handle in a clockwise direction, as viewed in Figure 2, will force the clamping element 53 and the sleeve 56 toward each other and cause them to clamp the workpiece positioned within the bore of sleeve 41.

As best shown in Figure 5, at each side of the stem 54 the sleeve 56 is provided with a bore 64 adapted to receive a plunger 65, which is forced downwardly by a spring 66. The plunger and springs, which are duplicated at opposite sides of the stem 54, separate the clamping element 53 and sleeve 56 when the handle 55 is rotated counterclockwise, and thus insure release of the workpiece. The fit of the cylindrical clamping element 53 and sleeve 56 in the transverse bore 52 is substantially accurate to prevent any appreciable leakage of fluid under pressure from the bore within sleeve 41.

The clamping ring 42, which serves to hold the sleeve 41 in position, is provided with a central opening in which is fitted a tubular housing 68. The housing 68 and ring 42 are fixedly secured together in any suitable manner, as by welding. The tubular housing 68 is of sufficient internal diameter to receive the workpiece and

provide, at least adjacent the outer end of the tubular housing, a space within the housing and surrounding the workpiece, for a reason hereinafter indicated.

The housing 68 may be of any desired length, but is preferably so proportioned that when the workpiece 69 is fitted within the sleeve 41 and seated against the ring 45 it projects outwardly beyond the end of the tubular housing 68, so that it may be readily grasped and removed by the workman.

The tubular housing 68 is provided at its free extremity with a tubular extension 70, which is removably secured to the end of the housing by means forming a bayonet joint. As best shown in Figure 4, the mechanism of the bayonet joint is formed by a sleeve 71 welded to the exterior of housing 68 and surrounded by a rotatable ring 72. Ring 72 is provided with a pair of pins 73, which extend inwardly into a pair of slots 74 in the ring 71. Pins 73 and slots 74 permit a limited rotation of the sleeve 72 relative to the housing.

The ring 72 is provided with an enlarged end portion 75 having a counterbore into which may be fitted an enlarged portion 76 on a ring 77, which is welded at 78 to the tubular extension 70. The enlarged portion 75 of the ring 72 is provided with conventional bayonet slots 79 adapted to interlock with pins 80 projecting outwardly from the enlarged portion 76 of ring 77. The enlarged portion 76 of the ring 77 is provided with a counterbore in which is mounted an oil seal 82 of any desired or conventional construction. As a result of this construction, the tubular extension 70 may be readily removed or attached to the end of the tubular housing 68 by simply rotating the sleeve 72 to release the bayonet slot connection, and the seal 82 prevents leakage of liquid under pressure from the interior of the housing and tubular extension.

The outer end of the tubular extension 70 is closed in any suitable manner, as by a closure plate 83, and the combined housing formed by the tubular housing 68 and extension 70 is of sufficient length to completely enclose the entire workpiece and also the cutting portion 84 of a broaching tool when the noncutting shank portion 85 of the broaching tool is projected entirely through the workpiece and into the pulling chuck 23 of the machine.

The tubular housing 68 is provided with a fluid line 87 which leads from any suitable source (not shown) of oil or other coolant under pressure to the interior of the housing 68. The means for supplying oil or other coolant to the interior of the housing 68 may be of any desired or conventional construction, but preferably includes a pump which is automatically started when the operator initiates the broach pulling movement of the cylinder slide 12. The hydraulic circuit valves and controls for actuating the cylinder slide 12, being of conventional construction, are not shown or described.

The machine of the present invention is operated in the following manner:

The tubular extension 70 is removed by manipulating its bayonet and slot connection with the tubular housing 68, and the workpiece is inserted to the position shown in Figure 4 in which its inner end abuts against the thrust ring 45. The workpiece is then clamped in that position by manipulation of the handle 55. Thereupon the broaching tool is inserted through the workpiece from its outer end until the entire non-cutting shank portion 85 of the broach extends

through the workpiece and into the pulling chuck 23. This leaves the cutting portion 84 of the broaching tool projecting from the outer end of the workpiece, as best indicated at Figure 4. The tubular extension 70 is then fitted over the projecting end of the broach and workpiece and secured to the tubular housing by the aforementioned bayonet and slot connection. Thereupon fluid under pressure is admitted to the tubular housing 68, and the machine is started to effect the broach pulling movement of the slide 12.

It will be observed that, inasmuch as the outer end of the tubular housing 68 as well as the tubular extension 70 are of larger internal diameter than the external diameter of the workpiece, the fluid coolant under pressure will flow from pipe 87 into the space surrounding the workpiece and broach and will completely immerse the broach in the fluid. In addition, the coolant, which is preferably under a relatively high pressure, will flow through the workpiece in a space surrounding the broaching tool. This flow of coolant under pressure through the broaching tool continues throughout the broach cutting stroke, and it will be observed that the flow is in the direction of the cutting stroke and hence will assist in the removal of chips. Since the space between the broach teeth and between the shank of the broach and the interior of the workpiece is exceedingly small, particularly in rifle broaching operations, and the fluid in housing 68 and tubular extension 70 is under high pressure, the rate of flow of fluid through the workpiece during the broaching operation is exceedingly high. This not only materially assists in chip removal, but facilitates cooling of the work and broach teeth during the long cutting stroke which the teeth must make in passing through the workpiece.

It will be noted that during the broach pulling operation the spiral lead bar 24 will effect a controlled rotation of the pull chuck and, consequently, the broach end thus will cause the broach teeth to follow the spiral path necessary to effect a rifling operation. It is obvious that where a non-spiral broaching operation is desired, the lead bar may be omitted. Moreover, under certain circumstances it may be possible to omit the spiral lead bar even when forming rifle grooves, provided the broach is constructed to follow its own spiral path and the pull chuck 23 is freely rotatable.

On completion of the broach pulling operation, the machine and the pump which supplies coolant under pressure to line 87 are both stopped, and the tubular extension 70 is removed from the end of housing 68. This tubular extension will at that time contain a substantial body of residual coolant, which may be permitted to flow onto a sheet metal pan 90 which underlies the tubular housing 68 and a major portion of the extension 70. Suitable means are provided for returning the coolant which falls in pan 90 to the tank or other source of coolant connected to the coolant pump.

If the broaching operation is to be carried out by the operation of two or more separate broaches in succession, the operator, on removal of the tubular extension 70, inserts a new broach into the workpiece and into the pull chuck 23 which, of course, must have been freed of the first broach and brought back to its starting position. The cycle of operations is then repeated, as above described. When the broaching operation on a workpiece is completed, whether by the

operation of one or more broaching tools, the operator removes the tubular extension 70 and withdraws the workpiece 69 from the sleeve 41 and housing 68, replacing it by a new workpiece. Thereupon, the cycle of operations is repeated.

- 5 It will be apparent that there is provided in accordance with the present invention a machine in which the difficulty of making a fluid-tight connection between the interior of the workpiece and a source of fluid under pressure is entirely 10 eliminated by positioning the workpiece within a housing filled with fluid under pressure. Since the only outlet to that housing is through the opening in the thrust sustaining ring 45, against which the work abuts with a heavy pressure during the broaching operation, no appreciable 15 leakage around the exterior of the workpiece and out of this opening is possible. Accordingly, the workman may simply freely insert the workpiece in position and then close the housing by attaching the removable extension 70. Moreover, since the sleeve 41 holds the workpiece in accurate alignment, it is unnecessary to provide a detachable support for the opposite ends of the workpiece.
- 20 25 While only one form of the invention is illustrated and described herein, it is apparent that variations in the details and design of construction may be indulged in without departing from the spirit of the invention or the scope of the appended claims.

What is claimed is:

1. In a pull broach machine for broaching the interior of a relatively long tubular workpiece, a member having a socket adapted to receive and fit one end of said tubular workpiece and support the workpiece in broaching position, an axial thrust sustaining shoulder associated with said socket and adapted to engage a portion of 35 said workpiece and sustain the thrust induced by a broaching operation, the bottom of said socket having an opening to permit passage of a broaching tool therethrough, a tubular housing fixed at one end to said member and enclosing the opposite projecting end of said workpiece, said housing being of sufficient length to also enclose the projecting cutting portion of a broaching tool when the non-cutting shank portion of the tool is projected through the workpiece from 40 said opposite end thereof and through said opening in the bottom of said socket, said tubular housing having a demountable free end portion to permit insertion and removal of the workpiece and insertion of the broaching tool, means to 45 grasp the shank of the broaching tool when it projects through said opening in the bottom of the socket and to pull the broaching tool through the work, and means to supply coolant under pressure to said housing to cause a flow of coolant through the workpiece in the direction of 50 movement of the broaching tool.

2. In a pull broach machine for broaching the interior of a relatively long tubular workpiece, a member adapted to abut against one end of the workpiece and sustain the axial thrust induced 55 by the broaching operation, said member having an opening for passage of a broaching tool therethrough, a tubular housing extending from said member toward the opposite end of the workpiece and entirely surrounding said workpiece, said housing being closed at its end and of sufficient length to also enclose the projecting cutting portion of a broaching tool where the non-cutting shank portion of the tool extends 60 through the workpiece and said member, means 65 70 75

within said housing for clamping and holding the workpiece in position within the housing and in abutment with said member, a control element for operating said clamping means extending through the wall of said housing, said housing having a demountable end portion to permit insertion and removal of the workpiece and insertion of the broaching tool, means to grasp the shank of the broaching tool when it projects through said opening in the bottom of the socket and to pull the broaching tool through the work, and means to supply coolant under pressure to said housing to cause a flow of coolant through the workpiece in the direction of movement of the broaching tool.

3. In a pull broach machine for broaching the interior of a relatively long tubular workpiece, a member adapted to abut against one end of the workpiece and sustain the axial thrust induced by the broaching operation, said member having an opening for passage of a broaching tool therethrough, a tubular housing extending from said member toward the opposite end of the workpiece and entirely surrounding said workpiece, said housing being closed at its end and of sufficient length to also enclose the projecting cutting portion of a broaching tool when the non-cutting shank portion of the tool extends through the workpiece and said member, means within said housing for clamping and holding the workpiece in position within the housing and in abutment with said member, a control element for operating said clamping means extending through the wall of said housing, said housing having a demountable end portion separable from the re-

mainder of the housing at a point along the length thereof intermediate the ends of the workpiece to permit insertion and removal of the workpiece and insertion of the broaching tool, means to grasp the shank of the broaching tool when it projects through said opening in the bottom of the socket and to pull the broaching tool through the work, and means to supply coolant under pressure to said housing to cause a flow of coolant through the workpiece in the direction of movement of the broaching tool.

4. In a pull broach machine for broaching the interior of a relatively long tubular workpiece, a work fixture including a tubular housing adapted to enclose the workpiece and the cutting portion of the broach and having a thrust sustaining abutment at one end, means to supply coolant under pressure to said housing, a sleeve mounted in said housing adjacent said abutment and adapted to fit one end of the workpiece and hold the entire workpiece in alignment with the path of travel of the broach, the opposite end of the work being freely suspended in said housing, means operable from the exterior of said housing for clamping the workpiece in said sleeve, said last named means comprising a pair of cylindrical elements movable toward each other in a transverse bore formed in the walls of said housing and intersecting the bore of said sleeve in offset relation, and means for forcing said cylindrical elements toward each other and into engagement with the workpiece.

HARRY H. GOTBERG,
BENEDICT WELTE.
